UNITED STATES PATENT OFFICE

JOSEPH LEDWINKA, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA

LATCH MECHANISM

Application filed January 9, 1926. Serial No. 80,165.

My invention is a simplification of the type of latch mechanism covered by the application of John P. Tarbox, Serial No. 68,958, filed November 14, 1925. This filed application covers an invention which has for its object the elimination of apertures and recesses in combination with the interlocking device of door latch mechanisms in combination with door windows of substantially 10 the full width of the door. The invention embodied the inter-position of a relatively thin interlocking member between the edge of the window glass or other extensible member and the plane of the inner face of the 15 jamb rail, and in particular embodied the interlocking device in the form of the glass run channel itself. This glass run channel is usually made of sheet metal of relatively thin gage whereby the glass is not substantially 20 removed from the plane of the inner face of the jamb rail and in effect still lies over against it.

The simplification achieved by my invention consists in providing an interlocking 25 member independent of the glass run channel whereby the channel remains fixed in position, and constitutes therefor a better guide and a firmer mounting for the extensible member, and the provision of elongated special guides is not needful. The structure, 30 therefore, becomes cheaper. I cut the glass run channel away or else inwardly offset its bottom to accommodate the interlocking member so that the body of the glass run 35 channel may still be secured directly to the inner face of the jamb rail.

In the accompanying drawings I show one embodiment of my invention. Of them—

Figure 1 is a horizontal cross section of 40 the jamb rail portion of a door and the associated door posts equipped with a latch mechanism according to the combination of my invention.

Fig. 2 is a sectional perspective view of the 45 post and the latch keeper.

Fig. 3 is a similar view of the adjoining section of the door and the outer portion of the latch mechanism, and

Fig. 4 is a perspective view of the inner portion of the latch mechanism.

The door is comprised of a jamb rail 10 of pressed metal having a double Z section, the intermediate arm of which Z constitutes the rabbet of the door. The body of the door rail or web is of but the single thickness of the metal. The outer paneling of the door 55 11 is secured to the outer arm of the Z section in the usual way. The inner panel or lock board 12 has its margin welded or otherwise secured to the inner arm of the Z section of the rail.

The door shuts by its jamb rail 10 against elements carried by the door post 13 which is in general of channel cross section and in a portion of its length at least, is provided with a rabbet (not shown) complementary in a general way to the rabbet formed by the intermediate arm of the Z section jamb rail of the door.

Housed within the body of the lower portion of the door when in lowered position is the window glass or extensible member 14. This is of substantially the full width of the door in both its lower and upper portions. Its edge 15 on both sides (only the jamb rail side is shown but the hinge rail side is similarly arranged) is removed from the plane 16 of the inner face of the jamb rail 10 only by the thickness of the belted glass run channel 17. This channel in the embodiment shown is formed by welding a small angle member or relatively thin section to the face 16 of the jamb rail in such position with respect to the intermediate arm of the Z section, or the rabbet of the door as to form with it the glass run channel. The depth of the angle member and of the intermediate arm or rabbet of the rail are substantially the same, whereby the depth of the glass run channel represents the depth of the opaque projection of this portion of the rail 10. When the extensible member is made of such substantial full width and therefore lies over against the web of the rail, the opaque projection of the window frame of the door is a minimum.

Inside of the extensible member 14 is provided that portion of the door latch mechanism which comprehends the sliding latch bolt 18. This latch bolt coacts with the keeper 19 secured to the jamb face of the post 13.

Inside latch operating mechanism designated generally 20 is provided for operating this latch bolt. This mechanism comprises (see particularly Figs. 1 and 4) an oscillating operating lever 21 pivoted on a lock plate 22 below the bolt by means of a pivotal member 23. This member 23 also carries a bell crank comprising arms 24 and 25, the former of which extends horizontally toward the jamb rail and the latter of which extends upwardly into a slot 26 formed in the inner face of the bolt 18 where it bears upon the rear wall of the slot. Lever 21 also passes through this slot and lies in the plane of the arm 25, whereby when the lever 21 is rocked about its pivotal member 23 rearwardly the bolt 18 is withdrawn. Bolt 18 is normally projected forwardly into engagement with the keeper 19 by means of a spiral spring 27 housed within a recess 28 formed 10 in the body of the bolt and bearing at its front end against the body of the bolt and at its rear end against an ear 29 projected into the slot 28 through the body of the lock plate 22. Preferably slot 28 communicates with slot 26 and the rear end of slot 26 is inclined inwardly and forwardly to accommodate the similarly inclined front edge of the lever 21. Bolt 18 is confined to the face of the lock plate by a retaining guide 30 appropriately secured to the lock plate and its front end projects through the out-turned end 31 of the lock plate. The lock plate is secured in position to the jamb rail by means of this out-turned end through any appropriate securing 20 means.

In spite of the fact that the extensible member 14 is substantially the full width of the door, latch bolt 18 may also be operated from the outside of the door. This is by means of an outside latch operating mechanism designated generally 32. This comprises a transversely extending horizontally disposed latch operating spindle having a handle (not shown) on the outside of the door. This spindle passes through the outer panel 11 and is appropriately journaled in a U-shaped frame 34 having its bight disposed rearwardly and its outer arm extended inwardly and secured by any appropriate means to the inner face 16 of the jamb rail 10. Spindle 33 between the arms of the U is provided with a latch operating arm 35 extending forwardly to the jamb rail. A spiral spring 36 surrounding the spindle biases this arm upwardly for the joint purpose, as will be seen, of keeping out lost motion and in keeping the latch handle in a defined position.

This outside latch operating mechanism 32 is connected with the inside latch operating mechanism by means of an interlocking device in the form of a member 37 disposed between the inside face 16 of the jamb rail 10 and the adjacent edge 15 of the extensible member. The interlocking device 37 is a relatively thin pressed metal member mounted

for vertical reciprocation in sliding engagement with the inner face 16 of rail 10. To accommodate it the glass run channel 17 has the portion opposite the latch mechanism cut away as indicated at 38 in Fig. 3 and Fig. 1 so that the interlocking device may lie flatly against the surface and occupy a veritable minimum of interior space. In the form indicated it is necessary only to cut away the outer branch of the angle member which forms the glass run channel 17 and it is not necessary to encroach to any extent upon the felt lining of the glass run channel. The outer wall of the glass run channel holds the member 37 in place on the outside. On the inside the device 37 passes through slot 39 in the rabbet of the door rail and thence inwardly through the entire main body of the door rail by way of slot 40. Slots 39 and 40 may be merged for the purpose of easy assembly if desired. The inner end 41 of this member connects by pin and slot connection 42 with the outer end of arm 24 of bell crank 24-25 of the inside latch operating mechanism 20. The outer end 43 of the interlocking device is bent first rearwardly along the outer wall of the channel 17, where it effects an enlarged sliding bearing surface for the body for itself, and thence outwardly where it effects a pin and slot connection 44 with the front end of the arm 35 operable from spindle 33 of the outside latch operating mechanism 32. The inturned outer arm of the lock plate 34 is also turned rearwardly to lie against the rearwardly turned portion of the inner end 43 of the interlocking device and further enlarge and align the bearings provided therefor.

Whenever it is desired to operate the lock from the outside, one has only to operate spindle 33 counter-clockwise (in the form shown) whereupon the vertically moving interlocking device 37 is moved upwardly (the extent of the cut away portion of the glass run channel 17 being sufficient to permit ample such movement), and in so moving through its inner end 41 operates the bell crank 24-25 to retract the latch bolt 18. At the same time when it is desired to operate the latch bolt from the inside, one has only to move the operating lever 21 rearwardly and the latch bolt is so operated. In this case the operation of the latch bolt results also in movement of the outside spindle 33, but when the spindle 33 is moved by reason of the independent mounting of lever 21 and bell crank 24-25 upon the pivotal member 23, lever 21 is not moved. Being desired to close the door at any time, one has only to slam it, in which case bolt 18 is retracted by the inclined surfaces of keeper 19 and ratcheted in place, or if desired, one may operate the bolt to opened position, close the door and then release the bolt.

The interlocking device 37 is extremely cheap to manufacture consisting of a simple stamping of sheet metal. It is entirely inde-

pendent of the glass run channel 17 and thereby permits that channel to be permanently fixed in place. At the same time due to its form and its mounting, it takes up no more space laterally than does the glass run channel which is to be provided in any event and appropriately lined.

Where I have used herein and in the following claims, the expression "an extensible member of substantially the full width of the body of the door" or a similar expression, it has reference more particularly to the relative extent of the door and extensible member or sliding window at the latch side of the door with which my invention is more particularly concerned.

Such embodiments of my invention and other modifications as fall within its generic spirit fall without question within the scope 20 of the appended claims.

What I claim as new and useful is:

1. A latch mechanism for an automobile door adapted to have an extensible member of substantially the full width of the body of 25 the door arranged for slidable movement in a run channel on the jamb rail of the door comprising inside and outside latch operating devices adapted to be mounted on the door on opposite sides of the projected path of movement of said extensible member, and an interlocking device between the operating devices enabling each of them to operate a latch bolt, which interlocking device extends around the edge of said extensible member, is separate 35 from the run channel therefor, and partakes of movement in the vertical plane.

2. A latch mechanism for an automobile door adapted to have an extensible member of substantially the full width of the body of 40 the door arranged for slidable movement in a run channel on the jamb rail of the door, comprising inside and outside latch operating devices adapted to be mounted on the door on opposite sides of the projected path of movement of said extensible member, and an interlocking device for connecting said operating devices extending around the edge of said extensible member separately from the run channel therefor, and partaking of a sliding vertical movement in its interlocking function.

3. A latch mechanism for an automobile door adapted to have an extensible member of substantially the full width of the body of 45 the door arranged for slidable movement in a run channel upon the jamb rail of the door, comprising inside and outside latch operating devices adapted to be mounted on the door on opposite sides of the projected path of movement of said extensible member, and an interlocking device between the operating devices for enabling the same to operate a latch bolt, said interlocking device comprising a thin sheet metal stamping projecting transversely 60 of the door in a plane parallel to the plane of

the door rail and extending around the edge of said extensible member, said interlocking device being separate from said run channel and partaking in its interlocking function of movement in the vertical plane.

4. In combination with an automobile door having a window guide arranged on its jamb rail adapted to accommodate therein a sliding window of substantially the full width of the door, a latch mechanism for said door comprising inside and outside latch operating devices mounted on opposite sides of the projected path of movement of said extensible member, and an interlocking device between the operating devices enabling each of them to operate a latch bolt, said guide having a portion of its body cut away to accommodate the interlocking device.

In testimony whereof I hereunto affix my signature.

JOSEPH LEDWINKA.
